CLAIM

The ornamental design for a fishing rod storage rack, as shown and described.

DESCRIPTION

FIG. 1 is a perspective view of a fishing rod storage rack design showing my new design, and showing the separated state of use.

FIG. 2 is a front view of a fishing rod storage rack.

FIG. 3 is a rear view of a fishing rod storage rack.

FIG. 4 is a left side view showing the fishing rod storage rack separated state of use.

FIG. 5 is a right side view showing the fishing rod storage rack separated state of use.

FIG. 6 is a top view showing the fishing rod storage rack separated state of use.

FIG. 7 is a bottom view showing the fishing rod storage rack separated state of use; and,

FIG. 8 is another perspective view of a fishing rod storage rack design showing the separated state of use.

Any shading is not features of the design but are utilized to illustrate the surface contours of the fishing rod storage rack design in the drawings. The broken lines shown in the figures are for environmental purpose only and form no part of the claimed design.

1 Claim, 8 Drawing Sheets
